UNITED STATES PATENT OFFICE.

LEWIS HALLOCK NASH, OF SOUTH NORWALK, CONNECTICUT, ASSIGNOR TO
THE NATIONAL METER COMPANY, OF NEW YORK, N. Y.

WATER-METER.

SPECIFICATION forming part of Letters Patent No. 459,332, dated September 8, 1891.

Application filed March 14, 1890. Serial No. 343,843. (No model.)

To all whom it may concern:

Be it known that I, LEWIS HALLOCK NASH, a citizen of the United States, residing at South Norwalk, in the county of Fairfield and State 5 of Connecticut, have invented new and useful Improvements in Water-Meters, of which the following is a specification.

The drawings illustrate a meter which embodies my present improvements in combination, and these drawings, in connection with the following description, are sufficient to enable others skilled in the art to employ and practice my said invention in forms which are at present preferred. It will be, however, 10 understood that my present invention is by no means limited to the precise forms of apparatus herein illustrated and described, as various modifications may be made without departing from its general principles or exceeding the scope of the concluding claims.

My present improvements relate to fluid-meters; and they consist of certain novel parts and combinations of parts which will be particularly pointed out in the claims.

25 In the accompanying drawings I have illustrated one form of meter embodying my present improvements, in which—

Figure 1 represents a vertical section taken on the line $y-y$ of Fig. 2, which is a horizontal 30 section, the piston being removed. Figs. 3, 4, 5, and 8 are similar sections showing the piston in different positions. Fig. 6 shows a modification. Fig. 7 is a vertical section taken on the line $x-x$ of Fig. 8, showing the connection of 35 the ports and passages; and Fig. 9 shows the differential register connecting-gear. Fig. 10 shows an enlarged view of the joint-bearing for the register connecting-arm.

The following is a description of the structures shown in the drawings: The cylinder A is formed with interior bearing projections h' to h^6 , which inclose and bound wall recess-spaces e' to e^6 , all opening into the case-chamber. The abutment B has projections g' to g^6 , inclosing and bounding recess-spaces f' to f^6 . Referring to Figs. 2 and 7, each case-recess has an inlet-port a' to a^6 opening through the case-head into the inlet-passage D and a discharge passage or channel d' to d^6 connecting said case-recess with the corresponding abutment-recess in certain positions of the

piston. Each abutment-recess has an outlet-port b' to b^6 opening through the case-head into the discharge-passage E, and each abutment-recess also has a supply passage or channel c' to c^6 connecting said recess with the corresponding case-recess in certain positions of the piston. The piston F is in the form of a hollow corrugated cylinder forming exterior projections of a shape to make intermittent joint-forming contact with the case-wall recesses and projections, while similar interior piston projections are of a shape to also make intermittent contact with corresponding abutment-recesses. In its movement 60 each piston projection enters in succession a corresponding case-recess, displacing the water therefrom in succession, and each recess is in succession filled from the other side as the piston leaves it, therefore a description 65 of such action of the piston in one recess-space will give a complete description of the action of the piston in every other similar recess-space. When the piston is formed of a thin cylinder, as shown in Figs. 1 and 8, I 70 prefer to provide it at one end with a web F', as shown in Figs. 1 and 7, which serves to keep the piston in form and as a convenient means to connect the registering apparatus thereto.

I may arrange the inlet and outlet ports as I shall now describe, or in any other suitable way. The inlet-ports a' to a^6 are placed at one side of the points of the case projections, so as to open into the spaces outside of the 85 piston, while the outlet-ports b' to b^6 are along the sides of the abutment projections, so as to open inside the hollow piston. The channel-passages d' to d^6 are arranged at the other side of the case projections and make the 90 communications between the case-recesses and the abutment-recesses for the escape of the water from the exterior measuring-chambers. The channel-passages c' to c^6 are arranged on the sides of the abutment projections opposite the outer ports, so as to make the communication between the case-recesses and the abutment-recesses to allow of the inflow of the water within the piston.

I will describe the operation of the piston 100 with reference to the case and abutment recesses e' and f' . The piston, being in the po-

sition Fig. 3, has just closed communication through the outlet-port a' to the space e' , and also closed communication between the spaces e' and f' through the recess-port c' . The exhaust-port b^2 is just ready to open into chamber f' . The water enters into the measuring-spaces exterior to the piston through the inlet-ports a^2, a^3, a^4, a^5 , and a^6 and into the spaces inside the piston through the channel-ports c^5, c^6 , driving the piston in the direction of the arrow 2, during which movement the water escapes from the interior spaces through the ports b^1, b^3, b^4, b^5 , and b^6 and from the exterior spaces through the channel-ports d^3 and d^4 , and the piston-lobe, entering the chamber e' , displaces the water therefrom. This action takes place until the piston reaches the position of Fig. 8, when water enters through ports a', a^2, a^3, a^4 , and a^5 and channel-ports c^4, c^5 , and c^6 and escapes through ports b^2, b^3, b^4, b^5 , and b^6 and channel-ports d^2 and d^3 . At this instant the piston has just made contact with the bearing-point h^6 , closing chamber e' and on the instant of opening channel-port d' to discharge the water therefrom into chamber f' , from which it escapes through port b^2 . When the piston moves to position, Fig. 5, the chamber f' is closed by the piston making contact with the bearing-point g' of the abutment, and the water escapes through the port d^2 , while the water still escapes through the channel-ports d' out at port b' . In this position the water enters through ports $a', a^2, a^3, a^5, a^6, c^2$, and c^3 and escapes through ports $b^1, b^2, b^3, b^4, b^6, d'$, and d^6 , driving the piston in the direction of the arrow 2 to the position shown in Fig. 4. During these movements the space e' has been completely emptied of water from one side of the piston-lobe 40 and filled from the other side, while the space f' has been nearly emptied and is being refilled through the channel-ports c' . The water now enters ports $a', a^2, a^4, a^5, a^6, c'$, and c^2 and escapes from ports $b^1, b^2, b^3, b^5, b^6, d^3$, and d^6 , 45 driving the piston in the direction of the arrow 2 to the position shown in Fig. 3 completing the cycle of its movement. Hence in every movement every case-recess is filled and emptied, and combined pressures in the recess-spaces cause the piston to make its movement while it also controls the inflow and outflow into and from the measuring-spaces.

In the modification shown in Fig. 6 the piston is not of a uniform thickness throughout, 55 as in the other cases, but its action is the same in all essentials.

In the construction shown in Figs. 1 to 6 the hydrostatical pressures inside and outside of the piston are nearly balanced by 60 reason of the uniform thickness of the piston, while in the modification there is a greater excess of pressure tending to force the piston against the walls of the abutment, due chiefly to the unequal thickness of the piston.

65 The meter may be made of any desired number of coacting bearing projections, and it is not necessary that the piston and case

projections should be formed of circular bearing ends symmetrically placed round the center of the case, as shown, but their form may 70 be varied. I have shown the ports as being placed in the lower head only; but it will be understood that they may be placed in the upper head only, or in both heads, if desired.

I have shown my invention as applied to a 75 meter the piston of which has an orbit motion, but no motion of rotation about its own center; but it may be applied in meters having a compound motion.

The register-connecting device shown consists of a gyrating arm j , having a ball-bearing in the case-cover G and its inner end loosely connected to the piston and its outer end connecting with and driving the registering mechanism. The inner end of the arm j is caused to move in a circular path, and its outer end will therefore describe a similar movement, which is communicated to the dial mechanism by a spur and an annular gear operating differentially. The spur-gear m is secured to the end of the arm j and then meshes with the annular gear n , which has internal teeth greater in number than those of the gear m , which, being carried by said arm, has a non-rotating gyrating movement within the 95 annular gear to revolve the latter. Hence the gyrating movement of the gear m will cause the gear n to rotate at each gyration a distance equal to the difference between the number of teeth in the two wheels. If desired, the relation of these gears may be reversed.

The joint in the case-cover for the gyrating arm is made as follows, viz: The case-cover has a recess to receive the ball-bearing j' , and directly below it the cover also has a larger recess to receive a flexible diaphragm p , which incloses the said arm and is clamped to the shoulder of the ball-bearing by a nut i upon said arm to form with said arm. The joint with the case-cover is formed by a spring-ring i' , which is sprung in a seat in the recess upon the diaphragm in a manner to hold it in place.

Referring to Fig. 3, it will be observed that 115 the wall projection, as h^6 , is not wide enough to touch both sides of the corresponding recess of the piston, and therefore in the movement of the latter there is a time in which the piston does not touch either side of the said case projection. Similarly the abutment projections act with relation to the walls of the interior piston-recesses, and therefore do not touch at times in the movement of the piston. Similarly the projections of the piston, both 120 inside and outside, act with relation to the recesses in the abutment and case, respectively, and therefore do not touch at times in the movement of the piston. This result is due to the conformation of the case and abutment 125 projections in their relation to the piston projections and not to any specific form of either. Therefore, other forms may be employed.

In an application for a patent filed by me

March 10, 1886, under Serial No. 194,725, and upon which Letters Patent No. 433,088 were granted under date of July 29, 1890, I have described and claimed, among other things, a 5 water-meter, in which there is a hollow piston, having joint-forming projections, arranged to make continuous contact with the case or with a fixed abutment, or with both, for forming the measuring-spaces to control 10 the flow of fluid into and out of the measuring-spaces through suitable ports. One of the features of my present improvements is that the piston projections are adapted to make intermittent contact both with the case and 15 with the abutment. Not all of the claims of my said application are limited to a piston making continuous contact on one or both sides; but some of them are broad enough to cover the structure herein described and others—such as, for instance, those having a piston with interior but without exterior projections or recesses.

Many of the details and combinations illustrated and above described are not essential 25 to the several features of my present invention, broadly considered. This will be indicated in the concluding claims, as the omission of an element or the omission of reference to the particular features of the elements 30 mentioned are intended to be formal declarations of the fact that the omitted elements or features are not essential to the invention therein covered.

Having thus described my invention, what 35 I claim, and desire to secure by Letters Patent, is—

1. In a water-meter having suitable inlet and outlet ports, a case having interior projections and recesses, and a fixed abutment 40 having exterior projections and recesses, in combination with a hollow piston having interior and exterior projections and recesses, all of said projections on the piston, case, and fixed abutment being narrower than the recesses, in which they respectively operate, so 45 as to make intermittent contact.

2. In a water-meter having suitable inlet and outlet ports, a case having interior projections and recesses, and a fixed abutment

having exterior projections and recesses, in 50 combination with a hollow piston having interior and exterior projections and recesses, all of said projections on the piston, case, and fixed abutment being narrower than the recesses in which they respectively operate, so 55 as to make intermittent contact, an inlet-port for each case-recess, an outlet-port for each abutment-recess, and channel-ports for each case and abutment recess located on opposite sides of the abutment bearing-points. 60

3. The combination, with the register mechanism and the piston of a water-meter, of a gyrating arm connecting these devices, and a differential register-connecting device consisting of a spur and an annular gear. 65

4. The combination, with the register mechanism and the piston of a water-meter, of a gyrating arm connecting these devices and a joint-forming device for said arm, consisting of a flexible diaphragm, a clamping-nut, and a spring-ring holding the diaphragm to make 70 the joint.

5. The meter-case having the inlet and outlet passages D and E, a corrugated interior wall-surface, and a corrugated abutment 75 forming an intervening continuous chamber, into which the wall-recesses of the case and of the abutment open, combined with the inlet-ports a' to a⁶, opening into the case-recesses, the outlet-ports b' to b⁶, opening into 80 the abutment-recesses, and the channel-ports c' d', &c.

6. The combination, in a water-meter, of a corrugated cylinder-wall, a corrugated central abutment, and a corrugated cylindrical 85 piston dividing the case-chamber into measuring-spaces, with an open port and a channel port for the measuring-spaces of the abutment and an open port and a channel-port for the measuring-spaces of the case-chamber. 90

In testimony whereof I have hereunto set my hand in the presence of two subscribing witnesses.

LEWIS HALLOCK NASH.
